UNITED STATES PATENT OFFICE.

NELLIE D. COLTON, OF BUFFALO, NEW YORK.

DESIGN FOR A CANNED-FRUIT IMMERSER.

SPECIFICATION forming part of Design No. 83,822, dated January 1, 1901.

Application filed October 25, 1900. Serial No. 34,398. Term of patent 7 years.

To all whom it may concern:

Be it known that I, NELLIE D. COLTON, a citizen of the United States, residing at Buffalo, in the county of Erie and State of New York, have invented and produced a new and original Design for Canned-Fruit Immersers, of which the following is a specification, reference being had to the accompanying drawings, which form a part thereof, and in the several figures of which like letters of reference refer to like parts.

Figure 1 is an elevation of the same. Fig. 2 is a top plan view thereof. Fig. 3 is a top plan view of the immerser proper. Fig. 4 is a top plan view of the immerser-supporter.

As represented in the drawings, the leading features of my design are the disk A, which is perforated with the elliptical holes c, the cylindrical stem B, provided with the rounded shoulder C, and the button a, shaped in its

central part with circular edges and having the circular elongated ends b. The outline of the upper surface of the button a is convex, as clearly shown in Fig. 1.

The circular immerser-supporter D is provided with a central slot or opening d, shaped to correspond with the shape of the button a, but slightly smaller in size.

Having thus described my invention, what I claim as new and useful, and desire to secure by Letters Patent, is—

The design for a canned-fruit immerser, as herein shown and described.

In witness whereof I have hereunto set my hand in the presence of two witnesses.

NELLIE D. COLTON.
